UNITED STATES PATENT OFFICE

2,460,339

SHIP PROPULSION MEANS

Diamond Diamantides, Massillon, Ohio

Application March 28, 1945, Serial No. 585,323

1 Claim. (Cl. 115—34)

1

This invention relates to a ship propulsion means, and has for one of its objects the production of a simple and efficient driving means for a ship's propeller, wherein the driving power is located above the water line to accommodate a minimum amount of space.

Other objects and advantages of this invention will appear throughout the following specification and claim.

In the drawing:

Figure 1 is a side elevational view of a ship, partly in section and illustrating the location of the propulsion means;

Figure 2 is an enlarged side elevational view of the propulsion means, portions of the support and encasing means being shown in section; and

Figure 3 is a sectional view taken on line 3—3 of Figure 2.

By referring to the drawing, it will be seen that 10 designates the power plant or engine which is located in the engine-room 11 located just below the top deck 12 of the ship 13. A driving pulley or other means 14 is driven by the engine 10 over which passes a steel chain, or other suitable type of belt 15. This belt 15 passes over and drives a suitable pulley or other type of wheel 16 which is located just above pulley 14, as shown.

A line shaft 17 is driven by the pulley or wheel 16, which shaft 17 carries a pulley or wheel 18 at one end. A driving belt 19, in the nature of a steel chain or other suitable type is driven by the pulley 18, and this belt 19 passes over the propeller driving pulley 20 located near the bottom of the ship 13. This pulley 20 drives the propeller shaft 21, upon which the propeller 22 is mounted. It should be understood that the pulley 20 is smaller than the pulley 18 and that the ratio of size may vary, the pulley 18 preferably being much larger than the pulley 20. Vertically extending encasing tubes 23 extend from the top deck 12 through the engine room 11, through the space between the decks 24 and 25, the ends of the tubes 23 being anchored to the decks 12 and 25. The driving belt 19 passes through these tubes 23 and is shielded thereby to prevent interference with the operation thereof. As shown, a housing 26 encloses the pulleys 16 and 18 and shaft 17.

2

The present device may be located in the stern of a ship to occupy a minimum amount of space and necessitate only a short propeller shaft. Because of the location of the parts, the propulsion means is readily accessible for repair and replacement and increased speed may be obtained with a reduction of fuel consumption.

Having described the invention, what is claimed is:

- 10 A ship of the class described comprising a stern having an upper deck, an engine-room located just below the upper deck, said ship having an intermediate compartment below the upper deck, and a lower deck below the intermediate compartment, a power plant located in the engine-room, a pulley driven by the power plant, a second pulley located above the first-mentioned pulley, a line shaft driven by the second pulley and located above the upper deck, a driving pulley carried by the line shaft and located above the upper deck, a propeller and drive shaft located directly below the driving pulley, a pulley carried by the propeller shaft, the last-mentioned pulley and a portion of the shaft being enclosed within the ship 15 below the lower deck, a belt passing over the driving pulley and the pulley carried by the propeller shaft, vertical encasing tubes enclosed within the ship and supporting the upper deck just below said engine room and resting on said lower deck, 20 said belt passing through said tubes and being protected thereby, and a belt passing over the first 25 and second pulleys for driving the line shaft.

DIAMOND DIAMANTIDES.
